HOWES BODFISH, OF PHILADELPHIA, PENNSYLVANIA, ASSIGNOR TO CO-OPERATIVE UTILITIES CO., INC., OF PHILADELPHIA, PENNSYLVANIA, A CORPORATION OF DELAWARE.

SPRAYING APPARATUS.

Application filed December 17, 1924. Serial No. 756,541.

To all whom it may concern:

Be it known that I, HOWES BODFISH, a citizen of the United States, and a resident of Philadelphia, county of Philadelphia, 5 State of Pennsylvania, have invented certain new and useful Improvements in Spraying Apparatus, of which the following is a specification.

The present invention relates to spraying 10 apparatus, and more particularly to means for projecting material in plastic form.

Some of the objects of the present invention are to provide an improved apparatus for spraying material of a plastic nature; 15 to provide a pressure operated spraying apparatus whereby the velocity and quantity of material can be proportioned as desired; to provide a plastic ejecting means wherein the material is subjected to a uniform discharging pressure throughout the area of 20 the applied force; to provide improved means for cleaning a spraying apparatus after use; to provide an improved piston discharging means for plastic material 25 sprayers; to provide a piston for material sprayers which eliminates the necessity of piston rods or guides; and to provide other improvements as will hereinafter appear.

In the accompanying drawings, Fig. 1 represents a side elevation in part section of a spraying apparatus embodying one form of the present invention; Fig. 2 represents a plan of the casing of the sprayer, and Fig. 3 represents a detail of the cover hinging means.

Referring to the drawings, one form of the present invention comprises a casing 10 in the form of an open-ended cylinder, the lower end of which is seated upon and closed 40 by a supporting base 11, while its opposite end is arranged to be closed by a cover 12. In the present construction, the casing 10 is removably fastened to the base by stud bolts 13, and leakage at the joint between 45 these parts is prevented by an annular packing 14 which encircles the closure portion 15 of the base 11. The cover 12 conforms in size and shape generally to the configuration of the upper end of the casing 10, and is attached to the latter by means of a hinge formed by a tongue 16, which is integral with the cover 12; two ears 17, formed on the casing 10 to receive the tongue 16 between them, and a bolt 18 passing through the tongue and ears for

pivotal action. Suitable bolts 20 are located at convenient intervals about the flanged edge of the cover 12, in order to clamp it rigidly to the upper end of the casing 10, and a packing ring 21 is provided 60 to prevent leakage at the joint between the casing 10 and the cover 12. It will further be noted that the body portion of the cover 12 is substantially conical in form and converges to a discharge opening 22, which is 65 co-axial with the longitudinal axis of the cylinder 10.

For the purpose of forcing the contents of the casing 10 out by way of the discharge opening 22, a piston 23 is provided, the 70 dimensions of which are such that it fits snugly within the cylindrical casing 10, and has sufficient length to form a bearing against the walls of the cylinder to resist any tendency of the piston to assume a position other than perpendicular to the walls of the aforesaid cylinder. That portion of the piston 23 which is disposed toward the material contained within the casing 10 is 75 preferably conical, so that when it is in its lowermost position or at the end of its non-working stroke, the lower circumferential edge of the cone surface will be substantially at the same level as a drain or clean-out opening 24, in the side of the casing 10, which is normally closed by a plug 25. The opposite end of the piston 23 is provided with a washer 25 of leather or other suitable material, which is fastened to the piston by studs 26 and is provided 80 with an annular flange 27 which extends parallel and in close proximity to the inner walls of the cylinder of the casing 10. This construction insures the piston operating pressure acting against the rear of the piston and within the flange 27, so that the latter is forced outwardly against the walls of the casing 10 and forms a leak-proof joint, while also helping to maintain the piston properly positioned transversely of the 85 cylinder. Preferably the piston 23 is held at the end of its non-working stroke by means of a stop 28, which is here shown as formed integral with the base 11 and projecting into the cylinder coincident with the longitudinal axis thereof.

For the purpose of actuating the piston 23 to cause it to move toward the cover end of the cylinder casing 10 and thus force the material towards and through the discharge

- outlet 22, the base end of the casing 10 is provided with a port 30 formed in the inner wall thereof and opening into the space between the piston 23 and the closure 15.
- 5 At one side of the casing 10 a supply pipe 31 for pressure fluid communicates with the port 30, while at another location a blow-off opening 32 is provided which is normally closed by a removable plug 33. The
- 10 pipe 31 is controlled by a valve 34, and connects with a main supply pipe 35, extending to a source of pressure. When the valve 34 is open, pressure is admitted back of the piston 23, and causes it to move in a direction
- 15 to expel the plastic material by way of the outlet 22.
- In order to project the material in spray form as it is discharged from the casing 10, the outlet 22 has a pipe 36 connected to a
- 20 fitting 37 which also receives a pressure supply pipe 38, preferably of the flexible type, which leads from the main supply pipe 35 and is controlled by a valve 40. The fitting 37 has a common discharge for the material
- 25 and pressure fluid by way of a pipe 41 which joins a flexible lengths 42, and carries a nozzle 43 on its free end. A valve 44 is arranged on the nozzle 43 for control purposes, and another valve 45 is located in the
- 30 pipe line 41 for a purpose to be explained.
- In the operation of the apparatus the casing 10 is filled with the plastic material which is to be sprayed, and this is done by swinging the cover 12 to the position shown
- 35 in dotted lines Fig. 1, so that access may be had to the piston chamber. The piston 23 is in its normal position at the lower end of the casing, resting upon the stop 28, and the device may be put into operation as
- 40 soon as the cover 12 is returned to its closed position and tightly clamped to the end of the casing upon the packing 21. In order to start the apparatus the valves 44 and 45 are opened, the valve 40 closed and the valve
- 45 34 opened sufficiently to admit the right amount of pressure which will cause the piston 23 to move toward the discharge outlet 22 and thereby force the plastic material out by way of the pipe 36, fitting 37 and pipe
- 50 42. When the discharged material reaches the fitting 37, the valve 40 is opened and pressure admitted by way of pipe 38 to the fitting 37, to thereby inject the material at the desired velocity from the nozzle 43, and
- 55 this velocity can be varied to suit conditions by regulating the amount the valve 40 is open, while the quantity of material delivered in a given time can be regulated by the amount the valve 3 is open. When the
- 60 spraying operation is completed and the casing 10 entirely emptied of plastic material the cylinder can be thoroughly cleaned by removing the plug 25, closing the valve 45 and opening the valve 40, whereupon
- 65 pressure fluid is discharged through the cyl-
- inder and effectively washes and cleanses it of any residue of material, so that the device is ready to operate upon recharging at some future time. If it is desired to clean out the lower portion of the cylinder below the piston 23, the plug 33 may be removed and pressure from the pipe 31 blown directly through this chamber by opening the valve 34.
- It will now be apparent that a complete unitary spraying apparatus for plastic material has been devised which is simple in construction and efficient in operation. Also the construction is such that the plastic material is subjected to a uniform pressure throughout its transverse area, while the space wherein the material is confined is unobstructed by connecting rods or any guide means for the piston, and because of this design the discharge outlet can be located co-axial with the axis of the cylinder, and in consequence the material pressure upon the piston is equally distributed from the center thereof outward and maintains the piston correctly centered within the casing. While the plastic material under the action of the piston moves as a mass toward and through the outlet 22, this condition is changed as soon as it enters the fitting 37, because it is there subjected to the pressure fluid from pipe 38, the velocity of which breaks up the mass and carries it along in the form of a disintegrated spray. Furthermore, by providing the pressure side of the piston with an annular flexible flange, the action of the pressure fluid is to expand this latter outwardly against the inner walls of the casing to thereby effectively seal the joint between the piston and the casing, which prevents leakage of pressure to the material side of the piston, and also assists in maintaining the piston properly centered. The cone-shaped end of the piston is desirable in that it allows plastic residue or liquid to collect at the lowermost point of the casing in line with the outlet 24, so that when the latter is opened this residue may be effectively blown out to clean the cylinder.
- While only a single form is shown in which this invention may be embodied, it is to be understood that the invention is not limited to any specific construction, but might be applied to various forms without departing from the spirit of the invention or the scope of the appended claims.
- Having thus described my invention, I claim:
1. In a sprayer for plastic material, the combination of a casing having an inlet for pressure fluid at one end, a cone-shaped closure for the other end of said casing having a centrally disposed outlet, a piston mounted in said casing between said inlet and outlet and guided along by the walls of said cas-

ing, pressure means connected to said inlet, pressure means connected to act upon material discharged from said outlet, and separate control means for said pressure means.

5. 2. In a sprayer for plastic material, the combination of a casing having an inlet for pressure fluid at one end, a cone-shaped closure for the other end of said casing having a centrally disposed outlet, a piston

10 mounted in said casing between said inlet and outlet and guided along by the walls of said casing, pressure means connected to said inlet, pressure means connected to act upon material discharged from said outlet, separate

15 control means for said pressure means and forming a passage through said casing for pressure fluid for cleaning purposes.

3. In a sprayer for plastic material, the combination of a casing having an inlet for pressure fluid at one end, a cone-shaped closure for the other end of said casing having a centrally disposed outlet, a piston

20 mounted in said casing between said inlet and outlet and guided only by the walls of said casing, a stop projecting into said casing to support said piston in normal position, and pressure means acting simultaneously upon said piston and upon material

25 discharged from said outlet.

30 4. In a sprayer for plastic material, the combination of a casing having an inlet for pressure fluid at one end and an outlet for material at the other end, a piston interposed between said inlet and outlet within

35 said casing, means for supporting said piston at the end of its non-working stroke, a clean-out opening located through the wall

of said casing substantially in the plane of the inner end of said cylinder, a plug normally closing said opening, pressure fluid means for simultaneously acting upon said piston for discharge purposes and upon material discharged from said outlet, and means to change the direction of flow of said pressure means when said plug is removed to clean said casing.

5. In a sprayer for plastic material, the combination of a casing having an inlet for pressure fluid at one end, a cone-shaped closure for the other end of said casing having a centrally disposed outlet, a piston mounted in said casing between said inlet and outlet and guided only by the walls of said casing, said piston having a cone-shaped face disposed toward said closure, and pressure means acting simultaneously upon said piston and upon the material discharged from said outlet.

6. In a sprayer for plastic material, the combination of a casing having an inlet for pressure fluid at one end, a closure hinged to said casing having a discharge outlet for plastic material at the other end, a piston freely movable between said inlet and said outlet, pressure means attached to said casing for moving said piston to force said plastic material out of said discharge outlet, and pressure means for spraying the material as it leaves said outlet.

Signed at Philadelphia, county of Philadelphia, State of Pennsylvania, this 8th day of December, 1924.

HOWES BODFISH.
